(57) **CLAIM**

The ornamental design for an orthopedic device, as shown and described.

DESCRIPTION

FIG. 1 is a perspective view of an orthopedic device showing the design;

FIG. 2 is a right elevational view of the orthopedic device of FIG. 1;

FIG. 3 is a left elevational view of the orthopedic device of FIG. 1;

FIG. 4 is a back elevational view of the orthopedic device of FIG. 1;

FIG. 5 is a cross-sectional view along line 5-5 in FIG. 4, showing the inner right face of the orthopedic device;

FIG. 6 is a cross-sectional view taken along line 6-6 in FIG. 4, showing the inner left face of the orthopedic device;

FIG. 7 is a bottom plan cross-sectional view taken along line 7-7 in FIG. 4; and,

FIG. 8 is a top plan cross-sectional view taken along line 8-8 in FIG. 4.

The broken lines are included for the purpose of illustrating environmental structure and form no part of the claimed design.
